UNITED STATES PATENT OFFICE

MARGARET L. BENZIE, OF NEW YORK, N. Y.

CORSET-STEEL PROTECTOR

Application filed May 4, 1929. Serial No. 360,531.

This invention relates to a protector or guard useful in conjunction with corset stays or steels.

One of the objects of the invention is the provision of a protector or guard designed and adapted when employed, to prevent stays or steels of a corset from puncturing the fabric, and so become displaced, and the ends thereof exposed, and apt to cause injury to the wearer of the corset.

Another object of the invention is the production of a protector or guard having provision for incorporating it in a corset structure, in protecting or guarding engagement with each end of a stay or steel, in one and the same operation of securing the stay or steel in place in the corset structure.

The nature of the invention and its distinguishing features and advantages will appear when the following specification is read in connection with the accompanying drawing, in which—

Figure 1, is a front view of a corset selected to illustrate the invention.

Fig. 2, is an enlarged fragmentary view of a section of the corset structure, showing the ends of a pair of stays or steels and one form of the protector or guard in applied position.

Fig. 3, is a section taken on the line 3—3, of Fig. 2.

Fig. 4, is a section taken on the line 4—4, of Fig. 2.

Figs. 5 and 6, are perspective views of the components of one form of protector or guard.

Fig. 7, is a plan view of one form of protector or guard.

Fig. 8, is a section taken on the line 8—8, of Fig. 7.

Fig. 9, is a perspective view of a second form of protector or guard.

Referring now more particularly to the drawing, it will be apparent that there has been shown a corset 10 selected to illustrate the invention. It is common practice to incorporate the stays or steels of a corset in pairs or singly by the use of a strip of fabric which is secured to the body of the corset by lines of stitching. By way of example,

the invention is shown in the drawing, and hereinafter described as applied to a pair of stays or steels 11. Use is made of a piece of fabric 12 having applied thereto small flat bendable metal pieces 13 each of which has teeth or burrs 14 on the opposite side edges thereof, which are clinched with the piece of fabric 12 to hold the metal pieces 13 in place. Two metal pieces 13 are thus secured to the piece of fabric 12 in spaced relation.

As shown most clearly in Figs. 7 and 8.

The piece of fabric 12 and metal pieces 13 constitute a protector or guard useful in conjunction with the ends of a pair of the stays or steels 11.

Before the stays or steels 11 are secured in place on the body of the corset, the protector or guard is applied to the ends of the stays or steels 11.

This is accomplished by bending the pieces 13 enabling the application of the protector or guard to the adjacent ends of the stays or steels 11.

Each metal piece 13 will be bent around the end of the related stay or steel 11. The piece of fabric 12 affords provision for incorporating the protector or guard in the corset structure, in one and the same operation of securing a strip of fabric 15 by lines of stitching 16 to hold the stays or steels 11 in place;

it being apparent that the lines of stitching pass through or take in the piece of fabric 12 shown most clearly in Figs. 2 and 4, there being one line between the metal pieces 13 and one line at one side of each of the metal pieces 13.

In this manner the stays or steels 11 are prevented from puncturing the fabric of the corset structure, cannot become displaced, and therefore the ends thereof will not be exposed and apt to cause injury to the wearer.

As shown in Fig. 9, the protector or guard consists of a piece of fabric 17 and one piece of metal 18, such protector or guard being adapted for use in conjunction with the end of a single stay or steel, for the purposes set forth.

I claim:

1. The combination of a stay, a tip, a piece of fabric, said tip embracing said stay and fabric, and said fabric projecting beyond the edges of said tip, whereby said tip may be

100

secured to an article by means of stitching passing through said fabric.

2. The combination of a stay, a metal tip, a piece of fabric, said tip being secured to said fabric and embracing said stay and fabric, and said fabric projecting beyond the edges of said tip, whereby said tip may be secured to an article by means of stitching passing through said fabric.

3. The combination of a stay, a metal tip, a piece of fabric, said tip having integral means securing the tip to said fabric, said tip embracing said stay and fabric, and said fabric projecting beyond the edges of said tip, whereby said tip may be secured to an article by means of stitching passing through said fabric.

10 Signed at New York, in the county of New York and State of New York, this 2d day of May, 1929, A. D.
